UNITED STATES PATENT OFFICE.

ARTHUR J. BRAUER, OF GLENDALE, AND FREDERICK P. WAGNER AND WALTER S. OVERTON, OF ST. LOUIS, MISSOURI, ASSIGNEES TO BRAUER BROS. SHOE CO., OF ST. LOUIS, MISSOURI, A CORPORATION OF MISSOURI.

METHOD OF MAKING BOOTS OR SHOES.

Application filed July 5, 1924. Serial No. 724,354.

This invention relates to boots or shoes and more particularly to a method of making the same.

One of the objects of this invention is to provide an improved method of construction adapted to cheapen the manufacture of certain classes of shoes.

Further objects will appear from the detail description taken in connection with the accompanying drawing, in which:

Figure 1 is an underneath view of the instep piece and its assembled lining as used in a shoe made in accordance with the method embodying this invention;

Figure 2 is a top view of the same instep piece after being perforated and stitched;

Figure 3 is a top view of the upper of a shoe embodying this invention with the instep piece secured thereto by the first stitching operation; and

Figure 4 is a view similar to Figure 3 showing the upper after the shoe lining has been attached to the upper and the instep piece.

In accordance with this invention a separate contoured instep piece, such as is often used in ladies' low shoes, has a lining applied thereto after which the instep piece with its assembled lining is perforated within the contour thereof in order to carry out the desired decorative effect, and the perforated parts are then stitched together around the perforation edges in a suitable manner. The instep piece is thus practically finished before attachment to the upper. This finished instep piece is then attached to the upper by stitching or otherwise, and finally the lining for the upper is attached to these assembled parts.

Referring to the drawing, 1 designates the instep piece proper which may be constructed of suitable leather properly finished on the outside and which may be formed in the shape shown. In order to provide a finished forward edge, the forward edge 2 of the piece 1 is turned under and glued or cemented down as illustrated in Figure 1. A suitable lining 3 of leather or other suitable material cut to conform to the shape of the piece 1 is then cemented or otherwise secured to the underside of the instep piece 1. In assembling these parts the lining 3 is attached to the piece 1 with its forward edge short of or back of the forward edge

2 of the piece 1. The purpose of this will be more clearly set forth hereinafter. When the lining has been attached to the instep piece, the assembled parts may be perforated with slots or other openings 4 in any desired pattern for decorative effect. After perforating the assembled parts, the same may then be stitched together by lines of stitching 5 as illustrated in Figure 2. This stitching serves to reenforce the cement in holding the lining in place and to insure against the possibility of the cement becoming separated from the piece 1, in which case the appearance of the shoe would be seriously impaired.

The instep piece 1 is now ready for attachment to the upper. The assembled upper including the vamp 6 and quarters 7 may then have the instep piece attached thereto as by a line of stitching 8 running around the forward edge of the instep piece. This line of stitching may be run close to the forward edge 2 and outside of the forward edge of the lining 3. In this way the instep piece 1 will be bound closely to the upper so as not to expose the edge of the lining 3. An improved appearance of the finished shoe is thus obtained.

The shoe lining may then be assembled within the upper and the same attached to the upper and to the instep piece by stitching or otherwise. In the embodiment illustrated in Figure 4 this attachment is made by a line of stitching 9 which runs in a continuous circuit around the forward part of the instep piece 1 and the margin of the quarters 7. The instep piece, the upper and the shoe lining are included in this line of stitching so that the same serves to bind the lining to the upper not only along the instep but also clear around the rear part of the quarters 7.

The shoe lining may be cut so that when the assembling operation described in the last paragraph has been completed a margin 10 of that lining will be left protruding inwardly from the stitched edge. This margin may now be trimmed off close to the line of stitching 9 so as to provide a smooth and neat finish.

It will be seen, therefore, that this invention accomplishes its objects in providing a shoe of improved appearance and of a rugged and durable construction. A sim-

ple and effective method of construction is also provided by means of which the shoe may be manufactured economically on a large scale.

5 It is obvious that various changes may be made in details of construction without departing from the spirit of this invention; it is, therefore, to be understood that this invention is not to be limited to the specific 10 details shown and described.

Having thus described the invention, what is claimed is:

1. In the art of making shoes, the method comprising, assembling an instep piece and 15 its lining, attaching the assembled parts to the upper, and attaching the upper lining to the upper and instep piece.

2. In the art of making shoes, the method comprising, cementing together an instep 20 piece and its lining, perforating the closely adhering assembled parts, stitching the assembled perforated parts, and attaching the lined instep piece when so perforated and stitched, to the upper.

25 3. In the art of making shoes, the method comprising, assembling an instep piece and its lining, perforating the assembled parts, stitching around the perforations, attaching the assembled parts to the upper, and attaching the upper lining to the upper and 30 instep piece.

4. In the art of making shoes, the method comprising, assembling a lining on an instep piece with the forward edge of the lining back of the forward edge of the instep 35 piece, and stitching the forward edge of the instep piece to the upper.

5. In the art of making shoes, the method comprising, cementing a lining on an instep 40 piece with the forward edge of the lining back of the forward edge of the instep piece, and stitching the forward edge of the instep piece to the upper.

6. In the art of making shoes, the method comprising, assembling a lining on an instep 45 piece with the forward edge of the lining back of the forward edge of the instep piece, perforating the assembled parts, and stitching together the forward edge of the instep piece and the upper.

7. A boot or shoe having an upper, an instep piece having a lining the forward edge of which is set back from the forward edge of the instep piece, and a line of stitches attaching the forward edge of the instep piece 50 to the upper.

In testimony whereof we affix our signatures this 6th day of June, 1924.

ARTHUR J. BRAUER.
FREDERICK P. WAGNER
WALTER S. OVERTON.
